UNITED STATES PATENT OFFICE.

JOHN L. MUSANTE, OF FREDERICK, MARYLAND.

PROPELLER.

1,233,126.

Specification of Letters Patent.

Patented Mar. 9, 1920.

Application filed December 22, 1915. Serial No. 68,189.

To all whom it may concern:

Be it known that I, JOHN L. MUSANTE, a citizen of the United States, residing at Frederick, in the county of Frederick and State of Maryland, have invented certain new and useful Improvements in Propellers, of which the following is a specification.

My invention relates to propellers for aeronautical purposes, in aeroplanes and air 10 ships, and for such other uses, as on boats or fans, for which the same are suitable.

An object of the invention is to provide a greater area of propelling surface to act upon the fluid in which propulsion is taking 15 place, without unduly increasing the number of propeller blades; also to prevent a portion of the fluid acted upon from escaping radially and to compel the same to escape rearwardly in a direction opposite to the direction of propulsion. Further objects of the invention are to obtain and utilize all of the advantages which are or may be inherent in the construction of propeller hereinafter described.

25 With such objects in view the invention consists in the parts and combinations thereof hereinafter set forth and claimed.

In order to make the invention more clearly understood I have shown in the accompanying drawings means for carrying the same into practical effect, without limiting the improvements, in their useful applications, to the particular construction which, for purposes of explanation, has been 35 delineated. In said drawings—

Figure 1 is an edge view or elevation of the propeller.

Fig. 2 is a rear elevation of the same.

Fig. 3 is a diametrical sectional view on 40 line II—II of Fig. 2.

Fig. 4 is a cross-section on a larger scale of one of the blades, on line III—III of Fig. 3.

Referring to the drawings, 1 is the hub of 45 the propeller having suitable means whereby it is attached to the driving shaft (not shown), such as a bearing 2 in which the end of said shaft may be fixed.

The blades of the propeller are indicated 50 at 3. In the construction illustrated these blades are shown as two in number arranged opposite to each other, such number being preferred; but it will be understood that the invention is not confined to any particular 55 number of blades. These blades are fixed to or integral with the hub.

A convenient means for attaching the blades is to cast with or fixedly attach to a metal hub a number of flanges 4, corresponding with the number of blades, and to 60 attach the blade members 5, 6 to said flanges by screws, bolts or rivets 7. Whatever method of attachment is adopted it must be very firm, strong and durable.

Each propeller blade comprises two of 65 said members, 5 and 6, each consisting of a plate of metal or wood of a strength sufficient to resist the strain imposed by that speed of revolution for which the propeller is designed. These plates are spaced apart 70 from each other, and the width of the intervening space 8 increases from the front to the rear edge of the blade (Fig. 4). The direction of revolution is indicated by the arrows (Figs. 2 and 4), and the narrower 75 entrance part of the slot is at the front edge of the blade and the wider discharge part of the slot is at the rear edge of the blade. Each blade is therefore provided with two surfaces to act on the fluid medium, the outer face of the member 6 and the inner face of the member 5, and the discharge of the fluid which has been acted on by the inner surface of the blade member 5 is promoted through the rear opening of 80 the space 8 by the flaring shape of the latter.

The inner ends of the blade members are or may be spaced apart by the flanges 4, and their outer ends are also spaced apart by suitable means, such as spacers 9 to 90 which the blade members are attached by screws, bolts or rivets 10. The spacers 9 may be formed integral with one of the blade members. Their weight and inertia is of value in maintaining continuity of 95 revolution and in aiding the engine in this respect.

The blades have been illustrated as substantially flat, but may be made of the known spiral contour. Also the pitch of 100 the propeller may be different from that shown, and varied according to requirements.

The space 8 may be made wider at the ends of the blades than at the hub. This 105 may be accomplished by shaping the front or rear blade member to curve or incline away from the other member. Or both blade members may be given such inclined or curved shape.

My invention is hereinabove set forth as embodied in a particular form of construc-

tion, but I do not limit myself thereto or to less than all the possible forms in which the invention, as hereinafter claimed, may be embodied and distinguished from prior devices.

5 The propeller as a whole is very light in weight and strong in proportion to the service which it is capable of rendering, the blade members serving to brace each other as well as to act on the air or other fluid as described.

10 The spacers 9 prevent some of the fluid acted on by the propeller, that which is in the spaces 8, from escaping radially and compel 15 it to pass rearwardly thus promoting the rarification of the air or partial vacuum in front of the propeller and increasing its power. The hold (so to speak) which the propeller obtains upon the air by means of 20 the interior spaces 8 of the propeller blades increases its stability in air, and the stability of an attached aeroplane.

25 It will be understood that each propeller blade may have more than two substantially parallel members 5, 6, in which case it will have two or more parallel spaces 8.

What is claimed is:

1. A propeller the blades of which are provided with an air passage extending 30 through the blades in an inclined direc-

tion and being wider toward its rear part and substantially parallel with the outer surfaces of the blades.

2. A propeller the blades of which are composed of two members arranged one in 35 front of the other, inclined relative to each other and attached together, one member having an exterior propelling surface and the other member having an interior propelling surface, said propeller comprising 40 a flanged hub to which the inner ends of said members are riveted, and means for spacing the outer ends of said members.

3. A propeller comprising a hub having 45 spacing lugs, blade members separate from said lugs and attached thereto at opposite sides of the same so as to leave a forwardly tapering air space between said members, and separate spacing members between the outer ends of each pair of blade members 50 and attached thereto.

4. A pneumatic propeller comprising a plurality of blades, each of said blades being composed of two members spaced apart and having their inner surfaces inclined toward each other in a direction toward the 55 front edge of the blade.

In testimony whereof I affix my signature hereto.

JOHN L. MUSANTE
